EXTENSION BIT

Edward Frey, Modesto, Calif.

Application April 21, 1939, Serial No. 269,263

1 Claim. (Cl. 77—69)

This invention relates to extension bits where-in a bit operates in conjunction with a drill or other suitable center; and an object of the invention is to provide an extension bit of this character having certain new and useful improvements over such extension bits as are now known and in use, and which will, in general, be stronger, more durable, and adjustable to greater accuracy than the present-day bit.

The invention together with its objects and advantages will be best understood from a study of the following description taken in connection with the accompanying drawings wherein:

Figure 1 is an elevational view of the extension bit.

Figures 2, 3 and 4 are sectional views taken substantially on the lines 2—2, 3—3 and 4—4, respectively, of Figure 1, and

Figure 5 is an elevational view of a slightly modified form of bit.

Referring more in detail to the drawings it will be seen that the improved extension bit, in the preferred embodiment thereof, comprises a shank 5 equipped as at 6 to facilitate attachment to a drill press, electric drill, or similar tool.

Intermediate its ends the shank 5 is provided with a transverse bore 7 in which is adjustably accommodated a cross-arm 8.

The cross-arm 8 is provided, as shown, with "SAE" threads cut into the corners thereof for substantially the full length of the cross-arm.

Threadedly engaged with the cross-arm 8 are lock nuts 9 which are adapted to be threaded home on the arm 8 against opposite sides of the bore portion of the shank 5 to secure the cross-arm at the desired position of adjustment transversely with respect to the longitudinal axis of the shank.

By providing the threads as above described greater strength is afforded for the lock nuts and the adjustment of the arm 8 is greatly facilitated.

At the end thereof opposite to the end 6 shank 5 is provided with a socket 10 which receives the squared portion of the drill 11, said squared end of the drill 11 being secured positively within the socket 10 through the medium of set screws 12.

At one end thereof the cross-arm 8 is diametrically enlarged and split as at 13 to provide an expansible and contractible head embodying complementary jaws 14, 15.

The jaws 14, 15 are provided with complementary notches 16 providing therebetween a non-

circular opening to accommodate the noncircular shank portion 17 of a bit 21, or the noncircular shank portion 18 of a slightly modified form of bit shown in Figure 5 and indicated by the reference numeral 20.

For expanding and contracting the clamping head 16, that is to say for drawing the jaws 14, 15 thereof toward and away from one another, there is provided a clamping screw 19 that has threaded engagement with the jaw 14 as clearly shown in Figure 2.

Also, for positively securing the shank of the bit 21, or 20, as the case may be, the jaw 14 of the clamping head is provided with a threaded opening 22 to accommodate a set screw 23 that 15 will, of course, bind against the shank of the bit to positively secure the same against axial movement through the opening provided by the notches 16—16 in the jaws of said clamping head.

From the above it will be apparent that arm 20 8 may be adjusted transversely relative to the shank 5 for positioning the bit 21, or 20, as the case may be toward or away from the drill 11, while the said bit 21, or 20, as the case may be, may have the shank portion thereof secured at 25 the desired adjustment within the opening 16 of the clamping head to secure the bit at the desired position of longitudinal adjustment with respect to the drill 11. Thus the bit 21, or 20, as the case may be, may be adjusted to control 30 the cutting depth thereof to substantially any degree desired.

It will also be apparent that the structure of the clamping head 16 is such that but slight movement of the jaws 14 and 15 is required to 35 positively clamp the shank of the selected bit therebetween. Consequently this expansion or contraction action of the clamping head 16 will in no wise tend to weaken said clamping head.

As is well known, in actual practice, as the 40 shank 5 is rotated the drill 11 and bit 20, or 21, as the case may be, perform their function the drill 11 boring a central hole thus providing a turning point or bearing for the bit 21.

It is thought that a clear understanding of the 45 construction, utility and advantages of an extension bit embodying the features of the present invention will be had without a more detailed description.

Having thus described the invention what is 50 claimed as new is:

An extension bit comprising a shank having a bit receiving socket in its lower end and an enlarged part adjacent said end, said enlarged part having oppositely arranged flat sides and a non- 55

circular opening passing through the enlarged part and opening out through said sides, a cross arm of non-circular shape in cross section but having its corners rounded and threaded, said cross arm passing through the opening, nuts threaded on the cross arm and one engaging one

flat side of the enlargement and the other the second flat side of the enlargement and means for holding a cutter in one end of the cross arm and at right angles thereto.

EDWARD FREY. 5
